Assistant Examiner — Rachel Wolfe

(57) **CLAIM**

The ornamental design for a lamp as shown and described.

DESCRIPTION**1.1** : Bottom**1.2** : Front**1.3** : Front view alternative position**1.4** : Left**1.5** : Left view alternative position**1.6** : Perspective**1.7** : Top

The areas hatched with light grey lines are not part of the claimed design; The right side view is omitted because it is a mirror image of the left side view; The design has alternative positions, which are shown in the views.
